UNITED STATES PATENT OFFICE.

CHARLES H. NORTON, OF WORCESTER, MASSACHUSETTS, ASSIGNOR TO NORTON GRINDING COMPANY, OF WORCESTER, MASSACHUSETTS, A CORPORATION OF MASSACHUSETTS.

SURFACE-GRINDING MACHINE.

1,108,779.

Specification of Letters Patent. Patented Aug. 25, 1914.

Application filed June 6, 1913. Serial No. 772,054.

To all whom it may concern:

Be it known that I, CHARLES H. NORTON, a citizen of the United States, residing at Worcester, in the county of Worcester and 5 State of Massachusetts, have invented a new and useful Surface-Grinding Machine, of which the following is a specification.

This invention relates to a machine for grinding flat surfaces, and the principal 10 objects thereof are to provide a practicable and efficient construction capable of use upon work of a great variety which will be capable of entire automatic operation, but yet in which the control by the operator can 15 be regained instantaneously whenever desired; to provide improvements in the belt shifting mechanism, the reversing mechanism, the means for traversing the grinding wheel and for raising and lowering it, where- 20 by the adjustments of the machine can be varied accurately and expeditiously for the purpose of changing the character of work, and improvements in the form and arrangement of the horizontal slide supports, so as 25 to protect and rigidly carry the slide.

The invention also involves improvements in details of construction and combinations of parts as will appear hereinafter.

Reference is to be had to the accompanying 30 drawings, in which—

Figure 1 is a front view of a machine constructed in accordance with this invention; Fig. 2 is a rear view thereof; Fig. 3 is an end view thereof; Fig. 4 is a plan view 35 of the driving and belt shifting mechanism; Fig. 5 is a side view of the belt shifting mechanism; Fig. 6 is a front view of the reversing mechanism; Fig. 7 is a sectional view of the same; Figs. 8 and 9 are details 40 of the same; Fig. 10 is a sectional view of the mechanism for raising and lowering the wheel mechanism; Fig. 11 is a front view of the same; Fig. 12 is a plan showing the arrangement for connecting the motor to 45 raise the wheel mechanism; Fig. 13 is a front view of part of the same; Figs. 14 and 15 are views similar to Figs. 12 and 13 respectively, with the parts in another position; Fig. 16 is a front elevation of the wheel 50 traverse mechanism; and Fig. 17 is a plan thereof.

The machine shown in the first three figures comprises a main bed 2 carried by supports 3, each consisting of a wedge having ears 4 extending up therefrom and carrying the bed itself upon these wedges. The ears are provided with adjusting bolts 5 by which the wedges may be moved to secure perfect adjustment of the bed. The ways 7 formed on the bed carry the sliding table 8. 60 Rising from the bed is a separate casting or standard 9 supporting many parts of the mechanism.

The main parts of the machine are driven from a motor A which transmits power by 65 a belt 10 to a counter shaft 11 arranged transversely in bearings in the bed. Located on this shaft is a wide-faced pulley 12 (Fig. 4) for operating the sliding table and reversing mechanism, a pulley 13 for operating 70 the grinding wheel mechanism, and a pulley 14 for operating the pump, as will appear hereinafter.

On the pulley 12 are straight and cross belts operating loose pulleys 15 and 16 and a 75 tight pulley 17 on a shaft 18 (see Figs. 4 and 5). This shaft 18 is located below the top of the rear of the bed but beyond the shaft 11. On the shaft 18 is a worm 19 meshing with a worm-gear 20 fast to a longitudinal quill 200 located in bearings on a casing 201 in the bed. Through the quill passes a shaft 202 on the ends of which are keyed dash pots 21^a having air passages 203 regulated by screws 204. Fixed to one of 80 the dash pots and therefore to the shaft 202 is a shaft 21 having a worm 22 meshing with a worm gear 23 on a transverse shaft 24 (Fig. 7). This shaft is provided with a bull gear 25. With this construction, the 85 worm shaft 21 and the shaft 202 connected thereto is slideable longitudinally relative to the quill 200 at the moment of reversal of the table travel, this longitudinal movement being yieldingly resisted by the air contained in the dash-pots. The momentum of the table is largely, if not entirely, reduced by the time the air in the active dash-pot has escaped, at which time the piston contacts with the end of the cylinder and the 90 parts operate as if rigidly connected. By 95 this arrangement the speed of operation is 100

greatly increased. The bull gear meshes with a longitudinal rack 26 on the sliding table 8 for operating the same.

On the front of an apron 29, which has 5 a bearing for the end of the bull gear shaft 24, is located a reversing lever 28 which is operated by the usual dogs 30 on the sliding table. The reversing lever is pivoted on a bolt 41 and is provided with a pair of oppositely extending arms 28^a connected with it at that point. These arms have handles extending along about the level of the ways, by which the operator can manipulate it by hand either in emergency or in cases in 15 which the travel is too small to permit the use of the dogs for controlling it. At the bottom this lever 28 engages with a sleeve 31 mounted on a rod 32 which reciprocates in bearings in a casing 33 on the apron, and 20 which carries a slider 34, as shown in Fig. 6.

Arranged between collars 35 engaging the ends of the slider 34 and loose on said rod 32 are springs 36. A projection 37 is provided on the slider 34 in position to engage 25 the sleeve 31 to operate the springs 36. The slider is provided at its ends with catches 38, and latches 39 are pivoted to the apron 29 to coöperate with said catches. The ends of said latches are turned up or formed 30 in cam shape. A floating or shifting lever 40 is provided with a slot which receives the pivot bolt 41 of the lever 28, and another slot at the bottom which receives a pin 400 in the lever 28, and it lies over a plate 42 35 fixed to the lever 28. This plate has sockets 42^a for a spring setting pin 43 on the end of the lever 40. Thus the floating lever can be set in an upper and in a lower position. This lever 40 is provided with outwardly 40 extending arms 44 at the bottom, which are provided with studs or rolls 45 which engage under the projecting ends of the latches 39. When the lever 40 is in its highest 45 position, it prevents the operation of both latches 39 and, therefore, the automatic operation of the reversing mechanism. When in its low position with the left hand latch 39 holding its catch 38, the sliding table 8 can move to the left until the upper end 50 of the lever 28 is engaged by the right-hand reversing dog 30. As this action takes place, the lower end of the lever 28 will be swung to the right, which will put the right-hand spring 36 under heavy compression 55 and as this swinging of the lower end of the lever 28 continues, the lower end thereof will finally engage the cam-shaped end of the right-hand latch 39 and will lift the same free of its catch 38. The 60 right-hand spring 36 will now throw the slider 34 to the right, which will cause the left-hand catch 38 to engage under the left-hand latch 39. This movement of the slider 34 to the right will rock the lower end of 65 the shifting lever 40 to the right, which

will throw the belt shifter rod 32 to reverse the motion of the work table, as will appear hereinafter. Thus the motion will be automatically reversed at the position determined by the right-hand reversing dog 30. 70 The work table will now move to the left and when the upper end of the lever 28 engages the left-hand reversing dog 30, the motion of the work table 8 will be reversed automatically at its left-hand extreme of 75 travel.

A lock for the reversing lever is shown in Figs. 6 and 9 as comprising a plate 46 having a notch 47 at the center for receiving the lever, and provided with an arm 48 80 for turning it on its own pivot. It is pivoted in brackets on the bed.

The way in which the rod 32 shifts the belt is very simple. It is connected by a bell crank 49 (Fig. 4) to another rod 50 85 which is connected with a sliding carriage 51. This has grooved wheels 52 (Fig. 5) arranged in pairs thereon and running between a pair of stationary parallel rods 53 constituting tracks therefor. The carriage 90 is provided with belt guides 54 for the two belts. The carriage 51 is supported by brackets 56 mounted on boxes 57 in which the shaft 18 is supported.

The standard or housing 9 is provided 95 with vertical ways 60 on which operates a vertical slide 61 having a horizontal hood 62 cast thereon. This hood is substantially semi-cylindrical on top and has a flat bottom provided with downwardly extending 100 projections having horizontal ways 63 (Fig. 16) at the bottom on their inner faces. The horizontal wheel slide 64 is carried by the ways. Thus the wearing surfaces of the ways and slide are protected by the hood 105 from the lodgment thereon of metal filings, chips and the like. This adds materially to the effective life of these parts. Also on account of the shape of the hood it furnishes a rigid support for both sides of the slide. 110 This is provided with downwardly extending brackets 65 (Fig. 2) for supporting the grinding wheel shaft 66 on which the grinding wheel 67 is fixed.

On the bottom of the slide 61 are downwardly extending brackets 68, at the bottom of which is pivoted a support 69 having bearings 70 thereon for the horizontal shaft of a wide faced pulley 71. The other side of this support 69 is supported from above 120 by a rod 72 having a spring 73 at the bottom, and adjustably mounted by a nut 74 at the top carried by a bracket 75 on the edge of the hood 62. The belt 76 which extends from the pulley 13 drives the pulley 71 and a weighted belt tightening device 77 is pivoted on the shaft 11 for keeping the proper tension on the belt. This long-faced pulley 71 is provided with another belt 78 which drives a pulley 79 on the grinding wheel 125 130

shaft 66. An idler 80 is shown supported from one of the brackets 65 for providing sufficient wrap around the pulley 79. This arrangement is provided so as to allow for the vertical and horizontal motion of the grinding wheel shaft which will be described hereinafter. From the pulley 14 a belt 81 (Fig. 2) extends over a pair of idlers, one of which, 82 is adjustable, and a pulley 83 on a vertical shaft 84. The lower end of this shaft is connected with a pump (not shown) mounted in a tank 85. This tank is mounted on rollers and can be moved out and in under a part of the bed of the machine. It is provided with a recess on the rear to clear the end of the shaft 18 and connected parts when the tank is pushed in to its extreme position. The pump delivers a stream of water from this tank through a flexible hose 86 to a pipe 87 (Fig. 3) and through a nozzle 88 (Fig. 16) under the grinding wheel 67 and in contact with the work D on which it operates.

The work, it is to be understood, is supported on a work table 90 (Fig. 7) which is fixed to the sliding table 8, the work table being provided with the usual T-slots for securing the work. The work table is provided with upwardly extending side flanges 91 and with an elevated end flange 92 (Figs. 1 and 2) for preventing the splashing over of the water on the parts below and also for providing a trough 93 (Fig. 7) at each side of the work table for collecting the water. This water then drains down through an outlet 94 (Fig. 2) on the rear of the work table into an open trough 95 extending along the side of the bed. This drains through an outlet 96^a into the top of the tank. The ways on which the sliding table moves are protected from the water by plates 96 (Fig. 7) secured thereon and extending inwardly therefrom. When it is desired to repair the pump or get at the parts of the tank, the latter is drawn out to the rear in Fig. 2, after the belt 81 is either disconnected or loosened by moving the idler 82. This also exposes the end of the shaft 18 and connected parts thereof.

Pivoted connected by a bar 97^a (Fig. 3) with the front of the wheel slide is a guard or water shield 97 adjustable lengthwise by means of a screw 98. This can be moved up on its pivots, which are connected by frictional joints, so as to permit access to the parts in the back of it.

For the purpose of operating the vertical slide 61 the upright or housing 9 is provided with a vertical screw 100 (Fig. 3) passing through one or more tapped holes on the back of the slide. At the top of this screw is a bevel gear 101 (Fig. 10) in a casing 102. Extending down from this casing is an integral branch casing 103 in which is a shaft 104 geared to the gear 101 and

having on the other end thereof a gear 105 meshing with a gear 106. This gear is located on a shaft 107 supported at one end in a bearing on an extension of the casing 103 and provided with an end washer 99 and 70 adjusting screw 99^a. This gear 106 is loosely mounted on the shaft 107 and is provided with a long hub 108 to which is keyed the hub of a gear casing 109. This casing has an external gear 110 on the back thereof 75 and an internal gear 111 on the front. On the end of the hub 108 are washers 112, and beyond them is a plate 113 keyed to the shaft 107. Beyond that is a hand wheel 114 loose on the shaft. At the end of the shaft there 80 is a screw 115 provided with a handle 119 adapted to be moved up on the screw against a washer 120 on the end of the hand wheel 114. The hand wheel is provided with an 85 operating handle 121.

Mounted on the hand wheel 114 is a shaft 122 having a pinion 123 thereon meshing with the internal gear 111. With this shaft is connected a handle 124 having a spring pin 125 operating over an index plate 126 90 fixed on the hand wheel 114. When the locking pin 124 is in one of the holes of the index plate, the rotation of the hand wheel 114 by its handle 121 will cause the shaft 107 and gear 106 to rotate with it. This 95 also, of course, carries the gear casing 109 and connected parts. The handle 124 can be operated to turn the internal gear 111 slowly and adjust the angularity of the several shafts 107, 104 and 100, thus securing a fine adjustment of the height of the vertical slide 61.

For the purpose of operating the vertical slide by power when desired, a motor C is shown in Fig. 12. The shaft of this motor 105 is connected by a friction device 130 controlled by a lever 131 with a bevel gear 132 which drives a shaft 133. On this shaft is slidably mounted a pinion 134 adapted in one position to mesh with the external gear 110. In Fig. 12 this pinion is shown in its position out of mesh with the gear. For the purpose of sliding this pinion back and forth, it is provided with a frame 135 (Fig. 11) having a handle 136 movable along the 110 shaft 133 with the pinion. Pivoted on this frame 135 is a latch 137 having a spring-pressed handle 138 and a pin 139 adapted to enter a hole 140 (Fig. 13) in the stationary casing in which these parts are located. 115 When in this hole, as shown in Figs. 11, 12 and 13, the pinion 134 is held in its position out of mesh with the gear 110. In this position a tooth 147 rigidly connected with the frame 135 comes in position against a pin 141 on a member 142 which swings about a pivot 143 on the stationary frame. A spring 144 (Fig. 12) normally holds this pivot member in the position shown in these figures. It is provided with a head or button 130

145 by which it can be turned on its pivot so as to bring the pin 141 up into the position shown in Fig. 14 out of the way of the tooth 147 and also out of the path of a stud 5 146 on the hand wheel 114. Therefore, in this position, the hand wheel can be turned in both directions if desired, and also the handle 136 can be moved back and forth to cause the pinion to come into or out of mesh 10 with the gear 110. The position of the parts when in this position is shown most clearly in Figs. 14 and 15. In this position the motor can be used by the manipulation of the handle 131 to positively rotate the screw 15 100 and raise or lower the vertical slide, or on the other hand, with the parts still in this position, the hand wheel 114 can be used when the friction device 130 is off to raise and lower the slide. But when the parts are in 20 the position shown in Fig. 12 the pinion can not be moved into mesh with the gear and not only that, but the hand wheel 114 can be moved in only one direction after the pin 146 engages the member 142, that is, the 25 direction to raise the slide.

For the purpose of reciprocating the wheel slide longitudinally with respect to the wheel shaft, the following mechanism is provided: The horizontal hood 62 (Figs. 16 and 17) is 30 provided with a bracket 150 supporting a casing 151. This casing supports a shaft 152 on which is keyed an operating hand wheel 153. On the opposite end a bevel gear 154 meshes with a bevel gear 155 on a shaft 156. 35 On the shaft 156 is a gear 157 meshing with the rack 640 of the wheel slide. Loose on shaft 152 is a worm gear 158 meshing with a worm 159 on a shaft 160 operated by another hand wheel 161. On each side of the 40 worm gear 158 are flanged collars 162. Both of these collars are keyed to the shaft 152, the right-hand collar, as viewed in Fig. 17, being fixed to the shaft, and the left-hand collar being slidable thereon. A tightening 45 nut 163 is provided for moving the slidable collar longitudinally to grip the worm wheel 158 so that the shaft 152 can be operated by the hand wheel 161. This constitutes the wheel traverse mechanism.

50 Thus, by the mechanism described, the operator can adjust the grinding wheel slide transversely with regard to the work, by hand either rapidly or slowly; can cause the vertical slide to move vertically by power; 55 can set the parts so that the same can be operated by hand at two speeds; or can throw in mechanism which will cause the work table to travel forward and backward automatically within the limits determined 60 by the adjustment of the two reversing dogs. It will be seen, also, that by the connections described, it is possible for the operator to control the feed movement entirely by hand, irrespective of the automatic reversing 65 mechanism.

The cushioning device for relieving the reversal strain and the improved structure for supporting the wheel slide are not claimed in this application, these features constituting the subject matter of certain divisional applications filed by me. 70

Although I have illustrated and described a single form of the invention and have shown it as applied to a single type of machine, I am aware of the fact that many 75 modifications can be made therein without departing from the scope of the invention as expressed in the claims. Therefore, I do not wish to be limited in these respects, but

What I do claim is:—

1. In a grinding machine, the combination with a base, of a screw connected therewith, a slide connected with the screw to be moved thereby and having means for supporting a grinding wheel, a shaft carried by 85 said base, a gear loose on the shaft, means for connecting said gear with said screw for rotating the screw, a gear fixed with respect to the first named gear, a shaft provided with a pinion thereon meshing with said 90 last named gear, and means fixed to the last named shaft and pinion for giving the pinion a planetary motion and rotating the gears.

2. In a grinding machine, the combination 95 with the base, of a vertical screw, a slide connected with said screw to be moved vertically thereby and having means for supporting a grinding wheel, a shaft, a gear loose on said shaft, means for constantly 100 connecting said gear to said screw for rotating the screw, a hand wheel loose on said shaft, a gear fixed to the hub of the first named gear, a shaft on said hand wheel having a pinion thereon meshing with the 105 last named gear, and means fixed to the last named shaft and pinion and mounted on the hand wheel for rotating the pinion and gears.

3. In a grinding machine, the combination 110 with the base, of a vertical screw, a slide connected with said screw to be moved vertically thereby and having means for supporting a grinding wheel, a shaft, a gear loose on said shaft, means for constantly 115 connecting said gear to said screw for rotating the screw, a hand wheel loose on said shaft, a gear fixed to the hub of the first named gear, a shaft on said hand wheel having a pinion thereon meshing with the last named gear, an index plate fixed on the hand wheel, an index arm fixed to the shaft and rotatable along the plate, and a spring-pressed pin on said arm for engaging in the 120 plate.

4. In a grinding machine, the combination with the bed and a vertically movable slide, means for raising and lowering the slide, a gear constantly connected with said 125 means for operating it, a shaft on which 130

said gear is rotatably mounted, an internal gear fixed to the first named gear, a hand wheel rotatably mounted on said shaft, an index mechanism on the hand wheel having 5 a pinion meshing with the internal gear, a plate keyed to said shaft and adjacent to said hand wheel, and means for clamping the hand wheel to said plate.

5. In a grinding machine, the combination with the bed, of a slide, means for raising and lowering the slide, a gear constantly connected with said means for operating it, a shaft on which said gear is rotatably mounted, an internal gear fixed to the first 10 named gear, a hand wheel rotatably mounted on said shaft, an index mechanism on the hand wheel having a pinion meshing with the internal gear, a plate keyed to said shaft and adjacent to said hand wheel, means for 15 clamping the hand wheel to said plate, an external gear fixed with respect to said internal gear, a motor, a shaft adapted to be connected with the motor, a pinion slidably mounted on said shaft for meshing with said 20 external gear, whereby the slide can be operated by the motor, and means for preventing the last named pinion from being moved into engagement with its gear.

6. In a grinding machine, the combination with the bed, of a slide, means for raising and lowering the slide, a gear constantly connected with said means for operating it, a shaft on which said gear is rotatably mounted, a gear, a motor, a shaft adapted 30 to be connected with the motor, a pinion slidably mounted on said shaft for meshing with said gear, whereby the slide can be operated by the motor, and means for preventing the pinion from being moved into 35 engagement with its gear.

7. In a grinding machine, the combination of a bed, of a slide movable up and down, a gear constantly connected with said slide for moving it, a shaft adjacent to said 45 gear, a pinion slidably mounted on said shaft for meshing with said gear, a frame in which said pinion is supported, having a handle for moving the pinion along the shaft, and means for locking said frame in 50 a position in which the pinion meshes with the gear.

8. In a grinding machine, the combination of a bed, of a slide movable up and down, a gear constantly connected with said 55 slide for moving it, a shaft adjacent to said gear, a pinion slidably mounted on said shaft for meshing with said gear, a frame in which said pinion is supported, having a handle for moving the pinion along the 60 shaft, a projection on said frame, and a pivoted member having a pin adapted to engage said projection and prevent the movement of the frame along the shaft toward the gear when said member is in one extreme 65 position.

9. In a grinding machine, the combination of a bed, of a slide movable up and down, a gear constantly connected with said slide for 70 moving it, a shaft adjacent to said gear, a pinion slidably mounted on said shaft for meshing with said gear, a slide frame in which said pinion is supported having a projection, a pivoted member having a pin adapted to engage said projection and prevent the movement of the frame along the 75 shaft toward the gear when said member is in one extreme position, said pin being in a position to move beyond the projection when the member is swung into its other extreme position, a hand wheel for 80 operating said slide independently of said pin, and a stop pin on the hand wheel in position to engage said member when in its first named position.

10. In a grinding machine, the combination with the bed, of a slide mounted to move vertically, a motor, means for connecting the motor with the slide for operating it, a hand wheel, an adjusting device on the hand wheel, means for connecting 85 said hand wheel and adjusting device with the slide for operating it by hand either slowly or rapidly, said slide having horizontal ways, two hand wheels, one for operating the wheel slide rapidly and the 90 other for adjusting it, and means for connecting said hand wheels with the wheel slide.

11. In a grinding machine, the combination with the bed, of a slide mounted to move vertically, a motor, means for connecting the motor with the slide for operating it, a hand wheel, an adjusting device on the hand wheel, means for connecting 100 said hand wheel and adjusting device with the slide for operating it by hand either slowly or rapidly, said slide having horizontal ways thereon, a wheel slide mounted to move in said horizontal ways, said wheel slide having a rack, a pinion meshing with 105 said rack for operating it, a shaft supported by said vertical slide for operating the pinion, and two hand wheels connected with said shaft, one for rotating the pinion rapidly and the other for adjusting it. 110

12. In a grinding machine, the combination with the bed, of a vertically movable slide having horizontal ways thereon, a wheel slide mounted to move in said ways, a shaft having a worm thereon supported 120 by said vertical slide, a worm wheel meshing with the worm, a shaft on which said worm wheel is mounted, means for fixing said worm wheel to the shaft, a hand wheel on the end of the shaft for operating said shaft independently of the worm wheel, and means connected with the shaft for moving said slide. 125

13. In a grinding machine, the combination of a reciprocable slide, a shaft for op- 130

erating said slide, a worm wheel loosely mounted on the shaft, a transverse shaft having a worm thereon for operating the worm wheel and adjusting the first named shaft, a hand wheel on the shaft, and means connected with said hand wheel for fixing the worm wheel to the shaft and disconnecting it therefrom at will, whereby the slide can be moved by either of said shafts.

14. In a grinding machine, the combination of a shaft, a worm wheel loosely mounted thereon, a pair of plates keyed to said shaft on opposite sides of the hand wheel, a nut on said shaft for forcing one of said plates toward the other and clamping the worm wheel between them, whereby the worm wheel will be fixed with respect to the shaft, a worm meshing with said worm wheel for operating it, a slide for carrying a grinding wheel, and means connected with said shaft for reciprocating the slide.

15. In a grinding machine, the combination of a vertically movable slide, a horizontally movable slide carried thereby, a grinding wheel shaft movable with the horizontal slide, a counter-shaft mounted on a stationary part of the machine, a movable support connected with said vertical slide, a pulley shaft mounted in bearings on said support, a belt for connecting the counter shaft for keeping the belt tight, a pulley on said grinding wheel shaft, and a belt connecting the pulley shaft with the grinding wheel shaft.

16. In a grinding machine, the combination with the bed, of a vertically movable slide supported thereby, a horizontally movable slide carried by the vertical slide, a grinding wheel shaft movable with the horizontal slide and having a pulley thereon, a movable support connected with the vertically movable slide, adjustable means for holding said support up, a pulley shaft carried by said support, a long-faced pulley on said pulley shaft, a belt extending from said long-faced pulley to the pulley on the grinding wheel shaft, and means supported by the bed for driving said pulley shaft in all positions of the vertical slide.

17. In a grinding machine, the combination with the bed, of a vertically movable slide supported thereby, a horizontally movable slide carried by the vertical slide, a grinding wheel shaft movable with the horizontal slide and having a pulley thereon, a movable support connected with the vertically movable slide, yielding means for holding said support up, a pulley shaft carried by said support, a long-faced pulley on said pulley shaft, a belt extending from said long-faced pulley to the pulley on the grinding wheel shaft, a counter-shaft carried inside the bed, a belt extending from the counter shaft to the pulley shaft, and a movable

belt tightener for said pulley having idlers for the two strands of the belt and provided with a weight and having a link pivoted to it and to said counter-shaft.

18. In a grinding machine, the combination of a vertically movable slide, a grinding wheel shaft movable with the slide and having a pulley thereon, a movable support connected with the vertically movable slide, yielding means for holding said support up, a pulley shaft carried by said support, a pulley on said pulley shaft, a belt extending from said pulley to the pulley on the grinding wheel shaft, a counter-shaft, a belt extending from the counter shaft to the pulley shaft, and a movable belt tightener for the pulley having idlers for the two strands of the belt and provided with a weight.

19. In a grinding machine, the combination of a vertically movable slide, a support pivoted to said slide and extending outwardly therefrom, a rod adjustably connected with said slide at a point above the support, a spring for connecting said rod yielding with the outer end of said support, a shaft journaled on said support and having a long-faced pulley thereon, a horizontal slide movable parallel with said shaft upon said vertical slide, a grinding wheel shaft carried by the horizontal slide and movable therewith and having a pulley thereon, and a belt connecting the pulley on the grinding shaft with the long-faced pulley.

20. In a grinding machine, the combination with the bed, of a counter-shaft journaled on said bed and located within it, a vertically and horizontally movable grinding wheel shaft, means connected with the counter-shaft for driving said grinding wheel shaft in all positions thereof both horizontally and vertically, a shaft in the bed parallel with the counter-shaft having tight and loose pulleys thereon, belts connecting the counter-shaft with the latter shaft, a sliding table on the bed, and a bull gear operated by said transverse shaft for reciprocating said table.

21. In a grinding machine, the combination with the bed, of a counter-shaft journaled on said bed, a grinding wheel shaft, means connected with the counter-shaft for driving said grinding wheel shaft, a shaft in the bed having tight and loose pulleys thereon, belts connecting the counter-shaft with the tight and loose pulleys, a shaft connected with the latter shaft, a sliding table on the bed, a bull gear operated by the last named shaft for reciprocating said table, a reversing mechanism mounted on the front of the bed, and a belt shifter operated by said reversing mechanism for shifting said belts.

22. In a grinding machine, the combination of a counter-shaft, a movable grinding

wheel shaft, means connected with the counter-shaft for driving said grinding wheel shaft, a shaft having tight and loose pulleys thereon, belts connecting the counter-shaft with the tight and loose pulleys, and a belt shifter provided with guides for said belts.

In testimony whereof I have hereunto set my hand, in the presence of two subscribing witnesses.

CHARLES H. NORTON.
